INCINERATION

William Raisch, New York, N. Y., assignor to Underpinning & Foundation Co., Inc., New York, N. Y., a corporation of New York

Application December 17, 1936, Serial No. 116,385

2 Claims. (Cl. 110—12)

The present invention relates to improvements in the treatment of material and especially to treatment in which moisture and volatile matter are removed from the solids, as by a drying operation, and the solids are then burned. This invention, although adapted for the treatment of other materials, is especially adapted for the treatment and disposal of waste materials such as garbage and sewage materials including sludge and screenings.

The principal objects of the invention are to provide novel, advantageous and efficient forms of apparatus and methods for effecting treatment of the general character specified.

Another object relates to an improved updraft tiered multiple-hearth furnace in which part of the hot combustion gases is withdrawn from the furnace in the upper part of the burning or lower section of the furnace and the remaining combustion gases are passed upwardly through the drying or upper section to dry the material passing downwardly to the burning section and take up the vapors thus evolved, and then are discharged from the furnace. A further object relates to an improvement in drying and burning material involving the passage of material through a chamber, the supply of preheated air to one end of the chamber and the burning of the material at such end, the passage of air and hot combustion gases toward the other end of the chamber the withdrawal from the furnace, at an intermediate point, of a part of the hot gases, and the withdrawal from the drying end of the chamber of the hot gases and vapors taken up thereby.

Another object relates to improvements in drying and burning or the like in which material to be treated is first dried and then burned while passing through a chamber, a current of air is passed into the outlet portion of the chamber countercurrent to the flow of material to support combustion, and part of the resulting hot combustion gas passing countercurrent to the material is drawn out of the chamber at an intermediate point and the remainder is drawn through the drying portion and out of the chamber, the ratio of the amounts of hot gases passing out at the intermediate part of the chamber and the inlet end of the chamber being varied as desired.

A further object relates to an improvement in which material to be treated is passed through a chamber and first dried and then burned, and a stream of air is introduced at the other end and together with hot gases resulting from the burning passed countercurrent to the flow of material, part of the combustion gases is withdrawn at an

intermediate point and part at the drying end, the part removed at the intermediate point is used to reheat the part withdrawn from the drying end to assist in eliminating odors, and the reheated gases are used to preheat the air introduced at the burning part of the chamber.

In carrying out the invention in a preferred form, use may be made of an updraft tiered multiple-hearth furnace in which material to be treated is introduced at the top and gradually passed downwardly from hearth to hearth through upper drying zones and lower burning zones until it is discharged from the bottom of the furnace. Air is introduced at the bottom of the furnace and hot gases are discharged from the upper part in a known manner and in order to control the furnace part of the hot gases may be removed at an intermediate point whereby the amount of hot gases passing through the drying portion may be controlled and the drying may even be effected at such a low temperature as to avoid the production of noxious odors. The hot gases withdrawn at the intermediate point may be utilized in a heat exchanger to reheat the hot gases laden with moisture vapor which were reduced in temperature while effecting the drying, and to eliminate any odors evolved in the drying portion. The reheated gases may be used to preheat air fed to the burning portion. The two streams of discharged gases of combustion are drawn through the heat exchangers by induced draft and the proportionate amounts of combustion gases discharged in the two streams may be varied for purposes of control such as control of the drying operation.

Other objects, features and advantages will appear upon consideration of the following description and of the drawing in which the figure is a sectional elevation.

Referring to the drawing, there is disclosed a multiple-hearth furnace 10 comprising a peripheral wall 11, a top 12 and hearths 13, 14, 15, 16, 17 and 18, above which hearths are corresponding compartments or zones. Preferably the material to be treated is introduced through the peripheral part of the top 12, as by means of a hopper 19 and a chute 20 extending through the top 12 and controlled by a pivoted door or gate 21 normally urged to closed position by means of a weighted arm 22.

Material introduced into the furnace through the hopper 19 and chute 20 is fed downwardly from hearth to hearth by rabbelling it inwardly to central outlets or openings 23 of the hearths 13, 15 and 17, and outwardly to peripheral outlets 24.

of hearths 14, 16 and 18. The hearth 18 is also the bottom and preferably has only one outlet 24 at its periphery provided with a chute 25 controlled by a pivoted door 26 normally urged to closed position by a weighted arm 27. In gas seal feeding devices such as shown at the top and bottom of the furnace, the doors or gates will open whenever the material accumulates thereon sufficiently to overcome the weighted arms and 10 as soon as the material is discharged from the doors they will close.

The rabbling means may comprise a central hollow driving shaft 28 and one or more arms 29 projecting over each hearth and provided with 15 depending blades 30 arranged at such inclinations as to move the material inwardly toward the central outlet 23 in hearths 13, 15 and 17 and toward the peripheral outlets 24 of the hearths 14, 16 and 18. The shaft 28 passes through the central 20 parts of the central openings 23 of hearths 13, 15 and 17 and at the top 12 and hearths 14, 16 and 18 through smaller openings provided with gas seals. The shaft 28 may be driven by means including a bevel gear 31 on the shaft, a bevel 25 gear 32 meshing with bevel gear 31, and a pulley 33 driven from any suitable source of power.

In passing downwardly through the furnace, the material is detained temporarily on each 30 hearth and agitated and rabbled toward the outlet or outlets thereof and passes downwardly therethrough. While passing downwardly through the furnace the material is first dried and then burned which action is aided by passing a stream of air and hot gases upwardly 35 through the furnace that is countercurrent to the flow of the material and along the path thereof. To this end, air is forced by a fan 34 through a heat exchanger 35 where it is preheated, and the air thus preheated is passed through a duct 36 into a burning compartment or zone in the lower part of the furnace.

The air flows upwardly through the burning zones and supports combustion by which hot 40 combustion gases are produced. A part of these 45 gases of combustion flow to the top of the up-draft furnace, in which there are no gas seals or valves to divide the furnace into a distinct drying section and a distinct burning section, and pass out of the upper part of the furnace 50 through a duct 37.

In order to control drying of material in the upper part of the furnace and to eliminate noxious odors which may be evolved in the drying, 55 part of the hot combustion gases may be withdrawn from the furnace, at a point intermediate with respect to the upper drying zones and lower burning zones, through a duct 38 and the higher temperature part of a heat exchanger 39 which serves to reheat the gases discharged from 60 the furnace through the duct 37. The gases thus reheated pass to the higher temperature part of the heat exchanger or preheater 35 where they serve to preheat the air supplied to the lower part of the furnace. From the higher temperature 65 side of the heat exchangers 35 and 39, the combustion gases are drawn through ducts 40 and 41, respectively, and a duct 42 into which they merge to an induced draft fan 43 by which 70 they are discharged to a flue or stack 44. The ducts 40 and 41 may be provided with dampers 45 and 46, respectively, to assist in controlling the operation of the furnace.

In the event that noxious odors are developed in the drying zones of the furnace, they 75 may be eliminated in the heat exchanger 39.

Merely for purposes of illustration, the operation will be described so as to refer to temperatures which might be obtained at various points. For example air at 60° F. supplied by the fan 34 to the preheater 35 may pass out of the heat exchanger 35 at a temperature of 700° and into the lower part of the furnace to assist in burning material dried in the upper part of the furnace. Part of the waste gases of combustion may be withdrawn from an intermediate 10 part of the furnace at from 1300° to 1500° and passed through the higher temperature part of heat exchanger 39.

The remaining waste gases of combustion pass upwardly through the drying zones and take 15 up large volumes of vapor or steam in connection with a temperature drop to a temperature of from 800° to 900° when these gases are discharged from the upper part of the furnace through the duct 37. From the duct 37, the 20 waste gases pass through the lower temperature side of the heat exchanger 39 and after being reheated therein pass, at a temperature of about 1200°, to the higher temperature part of the heat 25 exchanger 35 where in heating the fresh air, the temperature of the combustion gases drops to about 500° as these gases are discharged through duct 40.

The gases in the ducts 40 and 41 are drawn, under control by the dampers 45 and 46, into 30 the duct 42 by the induced draft fan 43 and discharged through the flue or stack 44.

It should be understood that various changes may be made and that certain features may be used without others without departing from the 35 true scope and spirit of the invention.

Having thus described my invention, I claim:

1. The combination with a multiple hearth furnace in which material is fed downwardly from hearth to hearth through compartments 40 above the individual hearths and the material is dried in a plurality of drying compartments in the upper part of said furnace and then burned in a plurality of burning compartments in the lower part of the furnace, of means for introducing air into a lower compartment of said burning compartments, means for discharging from an upper compartment of said burning compartments part of the high temperature gases of combustion leaving the remainder thereof to pass upwardly through the drying zones and be reduced in temperature while drying the material, means for withdrawing gases and vapors from the upper compartment of said drying compartments and burning odoriferous gases and vapors in said withdrawn gases and vapors by passing the gases and vapors into heat exchange relationship with the high temperature gases discharged from said upper burning chamber whereby offensive odors will be eliminated, 60 and means for preheating the air introduced into said lower compartment of the burning compartments by heat exchange with the gases and vapors heated by said hot combustion gases. 65

2. The combination with a multiple hearth furnace in which material is fed downwardly from hearth to hearth through compartments above the individual hearths and the material is dried in a plurality of drying compartments in the upper part of said furnace and then burned in 70 a plurality of burning compartments in the lower part of the furnace, of a heat exchanger, means for discharging from the upper compartment of said burning compartments part of the high temperature gases of combustion and pass- 75

ing the same through the high temperature side of said heat exchanger, leaving the remainder of the high temperature gases to pass upwardly through the drying zones and be reduced in temperature while drying the material, a second heat exchanger, means for withdrawing gases and vapors from an upper compartment of said drying compartments and passing the same through the low temperature side of the first mentioned heat

exchanger to burn odoriferous gases and vapors in the stream from the drying zones and then through the high temperature side of the second heat exchanger and means for passing air through the low temperature side of said second heat exchanger and into a lower compartment of said burning compartments. 5

WILLIAM RAISCH.
